PACKING MOLD

Harry C. Mack, St. Paul, Minn., assignor of one-half to Frank C. Wiegand, St. Paul, Minn.

Application March 24, 1939, Serial No. 263,877

3 Claims. (Cl. 22—152)

My invention relates to molds for casting soft metal packings usually of materials known as red metal and comprising a copper alloy. Such packings are used on pump rods and reciprocating rods and shafts of innumerable purposes and well known in the engineering field. The packings made with this device are of the type with a bore corresponding to the bore of a shaft on which it is to be used, having a straight body portion from whence it tapers down to a diameter preferably slightly larger than the bore, the packing comprising two registering halves with arcuate meeting faces tapering down to a straight edge longitudinal of the bore and said two edges being at diametrically opposite sides of the bore. Take-up on these packings is provided by any well known means engaging the larger end of the packing and bearing toward the smaller end the metal being wedged or forced inwardly into proper circumferential contact of the shaft.

This device is designed particularly to produce cast packings in most efficient manner and eliminating obstacles and certain difficulties hitherto present in casting, all as hereinafter fully described reference being had to the accompanying drawing, in which,

Fig. 1 is a top view of my casting device assembled and ready for pouring of metal and Fig. 2 is a front elevation of Fig. 1.

Fig. 3 is a diametrical sectional elevation as on line 3—3 in Fig. 1, comprising mainly an interior view of the rear half of the mold.

Figs. 4 and 5 are respectively a top and side elevation of a finished metal packing of the kind produced by my mold.

Fig. 6 is a front view of a casting of the type made in the mold.

Fig. 7 is a reduced-scale top view of my mold device, omitting the outer ring and showing the parts separated.

Referring to the drawing by reference numerals, like characters designating corresponding parts in the various views, Figs. 4 and 5 designate specifically the type of packing made with this mold, said packing comprising as a whole a ring 7 with a straight circular body part 8 from whence it is tapered as 9 to the opposite end, concentric of the bore 10. The packing 0 comprises two opposite halves designated 7L and 7R said halves having diametrically opposite and registering meeting faces 11 each an arcuate face, each half thus having a crescent-like shape.

The mold itself is illustrated in Figs. 1, 2, 3, 5 and 7 and is designed to produce two packing sec-

tions 7L' and 7L'' on one casting operation and in one piece such as designated 7A in Fig. 6, said two sections subsequently mounted on a mandrel and separated and formed to size by any suitable cutting tool.

In making castings of the material used in packings it has hitherto been a problem to dispose of or reduce certain gases generated during the casting process and this is one condition I have provided for.

This mold comprises an upright cylindrical two part mold preferably two identical half cylinders of which one designated 12R is the rear half and 12F the front half of the complete cylinder, their registering faces designated 13. The bore 15 of said mold is straight but its exterior may be flared downward slightly to an enlarged circular base flange 14. 15 is a metal cylinder closing ring adapted to be slipped downwardly over and about the two abutting sections and force them together. This ring has an aperture 17 arranged to be aligned with an aperture 16 in cylinder part 12F, and 18 is a cap screw inserted inwardly into and through said aligned apertures and its threaded inner end engages in a threaded radial bore 20. 19B is an upright circular core member 19 in the center of the mold.

This core comprises the interior member of the mold and is held in concentric spaced relation to the inner face of section 12F by means of an 30 upright spacer 20 with an arcuate inner face 20A and is suitably fixed to the core. The outer face of said spacer has two adjoining arcuate faces of which the right hand part designated 20B is of a diameter corresponding to the inner diameter 35 of section 12F and to the left thereof an arcuate face 20C extends upwardly and inwardly to the core 19. In the rear cylinder part 12R approximately directly rearward of spacer 20 is fixed in part 12R another spacer 21 with a short arcuate 40 face 21A contacting the core and from thence rearwardly this spacer is tapered in an arc outwardly toward the left and terminating at the inside wall of 12R at a point designated 22. This point (or vertical line) 22 in part 12R is diametrically opposite from point 23 in cylinder part 12F and which latter point marks a vertical line on the inside wall where the arcuate face 20C starts. The inner arcuate face of spacer 21 which extends to point 22 is designated 24. Faces 24 and 20C form the opposite end faces of a casting made by pouring molten metal into the mold at any open place to the left of the core, such place being designated by a dotted circle 25 in Fig. 1. 55

A designates the space filled by molten packing metal, the general shape of the resultant casting being a crescent as seen from the top end.

Any size of metal packing ring of the kind described may thus be cast. The inside diameter of cylinder 12R-12F is the desired outside diameter of packing ring and the core 19 is of a diameter to produce a bore in the casting of a size according to bore wanted in the cast ring.

10 The opposite inclined (arcuate) faces of the casting thus made by faces 24 and 28C of the mold, form the opposite end faces 11 of a packing ring section.

In the use of my mold a pair of packing sections 9 are cast at one time, in one piece having certain parts readily cut to separate them for finishing. This is done by providing in each cylinder section 12R and 12F, intermediate its top and bottom ends, an arcuate rib or inward projection extending each to the left from the spacer 21 or 20 as the case may be, this rib in the rear section designated 26R and in the front section 26F. Each terminates in proximity to the left side meeting faces 13, and each rib extends to 25 horizontal plane, having an inner face 26A concentric of the inner wall of the section and also concentric of and in spaced relation to core 19. The upper and lower sides 26W of each rib are flared to the adjacent wall the incline of such 30 flare determining the taper 9 of the dual packing casting (see dual casting illustrated in Fig. 6).

In pouring the molten metal a vertical metal rib 27 is made (see Fig. 6) because of the open space between the adjacent ends of the mold 35 ribs 26W, said space designated 28 in Fig. 1.

In making a casting the mold is first set on a sandy surface 29, a top piece comprising in part a disc of plastic or porous material is used to cover the mold and is provided with a passage 40 to pour the molten metal in at 25. The sand or other porous material thus used to close both ends of the mold permits seepage or outlet of gases generated by the poured metal and which is an important feature in the process of casting 45 the packing.

A casting thus made is of the form shown in Fig. 6 having the upright connecting web 27 and a semi-circular web 30 formed in the space between the rib faces 26A and the core 19.

50 Subsequently the casting as shown in Fig. 6 may be mounted on a mandrel 31 (shown dotted) corresponding in diameter to the diameter of core 19 and recured to the mandrel in any suitable manner. Then put in a lathe and cut 55 and turned to finish the angular faces 9, which cuts are made deep enough to a common central line 32 this finishing cutting apart the upper and lower packing members originally in one casting. Thus is produced and finished a pair of 60 packing ring members which are not mated, having taper areas 9 in opposite plane. However mated pairs to these are made by mold means similar to those described but with the spacers 21, 20 and ribs 26W in diametrically opposite positions to those illustrated.

In the use of my mold it is obvious that the device comprises a minimum number of parts readily assembled for casting and also readily taken apart or opened after casting. In assembling the cylindrical parts 12R and 12F are first

set up face to face at 13. Then the core member 19-19B slipped downwardly into place and which will simultaneously contact the inner face 21A of the crescent shaped part 21. The ring 15 is then slipped downwardly over the cylindrical housing and the screw 18 is inserted radially and drawn up, thus holding the parts firmly together. A dowel 33 is further provided to be inserted radially inwardly through registering bores in cylinder 12R block 21 and into core 19 (over ring 15). This provides further stability and connection of parts in concentric relation.

I claim:

1. A mold for making soft metal tapered packings of the class described, said mold comprising 15 a bisecting upright cylinder, a ring member inclosing said cylinder members and holding them firmly together in registering positions, a central upright core in said cylinder, spacer means to removably retain and position said core centrally 20 in the cylinder, said spacer means comprising a pair of arcuate blocks one fixed to the interior wall of one cylinder section and the other integral of the core, both blocks of a height corresponding to the height of the cylinder, each block having a thick end contacting the cylinder wall, each block having further an arcuate face traversing the space between the cylinder wall and the core, said faces in diametrically opposite relation to the center of the core, an arcuate rib 25 in horizontal plane and integral of the inner face or wall of the cylinder and intermediate its top and bottom ends, said rib having an inner face in vertical plane and in spaced parallel relation to the core and flared thence to the wall 30 of the cylinder.

2. The structure specified in claim 1, in which said cylinder is tapered upwardly, exteriorly, said ring having a correspondingly tapered bore and adapted to be passed down over the cylinder to 40 a predetermined level, said cylinder wall, the ring and the core provided with radially registering bores, the bore in the core being threaded, a set screw insertible in said aligned bores and threaded into the core, and a dowel insertible 45 radially into the cylinder, through a spacer block and into the core, in spaced relation to said set screw and over the ring member, for the purpose set forth.

3. A packing mold comprising an upright cylindrical body adapted to rest on a flat surface 50 of porous material, a central core member within said cylinder, the open upper end of the cylinder adapted to be closed by a plate or the like of porous material and provided with a bore for access to pour molten metal into the cylinder between the core and the walls thereof, upright spacer blocks between said core and the inside walls and having arcuate inwardly exposed faces traversing the space between the core and the 55 inside walls, horizontal rib members integral of the said inside walls said ribs flared to the inside walls, said arcuate faces and the flared ribs proportioned to produce of metal poured into the mold a pair of vertically spaced and connected 60 half-sections of packing rings each with a straight, round outer portion and a portion tapered toward its bore formed by the core member of the mold.

HARRY C. MACK. 7
